(57) **CLAIM**

The ornamental design for a hair dye applicator as shown and described.

DESCRIPTION

FIG. 1 is a front, right and top perspective view of a hair dye applicator, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is another front, right, and top perspective view of the hair dye applicator shown in an alternate configuration with a cap; and,

FIG. 11 is an exploded front, right and top perspective view of the hair dye applicator in FIG. 10.

The dashed broken lines depict portions of the hair dye applicator that form no part of the claimed design. The dot-dash broken lines in FIGS. 1 and 9 depict the boundaries of the enlarged views and form no part of the claimed design.

1 Claim, 11 Drawing Sheets
